CLAIM

The ornamental design for a hair drier, as shown and described.

DESCRIPTION

1. Hair drier

1.1 : Perspective

1.2 : Front

1.3 : Back

1.4 : Left

1.5 : Right

1.6 : Top

1.7 : Bottom

Hair drier; A new, original, and ornamental design for a hair drier, of which the following is a specification, reference being had to the accompanying drawings, forming a part thereof wherein: FIG. 1.1 is a perspective view of our new design, showing a hair drier; FIG. 1.2 is a front elevation view thereof; FIG. 1.3 is a rear elevation view thereof; FIG. 1.4 is a left side elevation view thereof; FIG. 1.5 is a right side elevation view thereof; FIG. 1.6 is a top plan view thereof; and FIG. 1.7 is a bottom plan view thereof.

The broken lines shown in the reproductions illustrate portions of the hair dryer that form no part of the claimed design.
